(57) **CLAIM**

The ornamental design for a light belt, as shown and described.

DESCRIPTION

FIG. 1 is a front, right, and top perspective view of a light belt, showing my design.

FIG. 2 is a rear, left, and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising an upper part;

FIG. 10 is a partial enlarged view of an area labeled 10 in FIG. 1 comprising a switch portion.

FIG. 11 is a partial enlarged view of an area labeled 11 in FIG. 2 comprising a lamp group element; and,

FIG. 12 is another perspective view of the light belt wherein the upper part and the lower part are buckled together. Dot-dash broken lines framing portions of the claimed design that are illustrated for enlargements form no part of the claimed design.
